Filed Aug. 8, 1961, Ser. No. 66,240

Term of patent 14 years

(Cl. D4—2)

FIG.1

FIG.2

FIGURE 1 is a view in perspective of the combined lavatory, water closet and cabinet;

FIGURE 2 is a fragmentary front view showing a portion of the left side of the lavatory cabinet and a portion of the area to the left thereof.

The rear and side not shown are substantially plain. The side of the lavatory cabinet not shown is substantially identical to that shown, except as indicated. The side of the water closet not shown is substantially identical to that shown.

The dominant features of the design reside in the portions shown in full line.

I claim:

The ornamental design for a combined lavatory, water closet and cabinet, substantially as shown and described.
